UNITED STATES PATENT OFFICE.

HUGO LENTZ, OF MAUER, NEAR VIENNA, AUSTRIA.

TWIN COMPOUND MARINE STEAM ENGINE.

Application filed September 29, 1920. Serial No. 413,656.

To all whom it may concern:

Be it known that I, HUGO LENTZ, a citizen of the German Republic, residing at Mauer, near Vienna, Austria, have invented certain new and useful Improvements in Twin Compound Marine Steam Engines, of which the following is a specification.

This invention relates to a twin-compound marine steam engine, in which the cranks of one compound engine are displaced 90° with regard to the cranks of the other compound engine, the cranks of the high-and low-pressure cylinders of each compound engine being displaced 180° the one with regard to the other, the exhaust valve of the high-pressure cylinder forming at the same time the inlet valve of the low-pressure cylinder according to Woolf's principle, so that no receiver is required. In order to ensure the most profitable steam distribution the high-pressure cylinders are preferably arranged in the middle, the low-pressure cylinders being situated at the sides. With each compound engine an eccentric and lay shafts are connected for the simultaneous control of all the valves of each engine. The two reversing links can be made in one piece according to this improved form of construction, so that the reversing gear not only becomes simpler but is more accessible for repairs.

In the drawings:—

Fig. 1 is the front elevation of an improved engine.

Fig. 1^a is a plan view of the crank shaft of the engine shown in Fig. 1.

Fig. 2 is a side elevation of the engine.

Fig. 3 is a plan view, the middle part being shown in section.

Fig. 3^a is a vertical section through one of the high-pressure cylinders and the corresponding reversing gear casing comprising the inlet valves.

Fig. 4 shows the valve operating and reversing mechanism of one compound engine on a larger scale in side elevation, the position of the reversing mechanism of the other compound engine being indicated by dotted centre lines.

Fig. 5 is a front elevation of the link in section on line V—V of Fig. 4 and seen in the direction of arrow A (Fig. 4).

Fig. 6 shows the diagram of the valve operating and reversing mechanism in the position for the forward and backward motion, showing only the gear mechanism for the valves of the top cylinder head.

The engine consists of the two high-pressure cylinders 1, 1' and of the two low-pressure cylinders 2, 2' which, by means of the standards 3 and supports 4, are mounted upon the bed plate 5. The high-pressure cylinders 1, 1' are situated advantageously at the middle and the low-pressure cylinders 2, 2' at the sides. The crank shaft 6 mounted in the bed plate is driven from the several cylinders by means of connecting rods 7 in the manner usual with vertical marine steam engines. One high-pressure cylinder and one low-pressure cylinder form together a compound steam engine in which the exhaust valve of the high-pressure cylinder preferably forms also the inlet valve of the low-pressure cylinder. The cranks of each of these compound engines are displaced 90° with regard to each other, the cranks of the high- and low-pressure engines of each compound being displaced 180° the one to the other (Fig. 1^a).

The link motion of each of these compound engines is operated by single eccentrics 8, 8' respectively, shown in full and dotted lines on Fig. 4, which are keyed upon the crank shaft 6 near the middle. An eccentric rod 10 attached to the eccentric strap 9 which surrounds the eccentric 8, has a pin 11 at the middle upon which a sliding block 12 is mounted which slides in the link 13. The oscillating lay-shaft 31 is driven from the eccentric rod 10 by means of a connecting rod 15 mounted upon a pin 14 fixed in the end of said individual eccentric rod 10. Fig. 4 shows the described reversing mechanism of one compound engine. The position of the reversing mechanism of the other compound engine, which is not visible on the drawing, is indicated in dotted centre lines.

Each of the two compound engines is provided with an eccentric drive for the control of the inlet valves 33 the intermediate valves 34 between high-pressure and low-pressure cylinder and the outlet valves 35. The two eccentrics are situated close together near the middle of the engine. The corresponding links 13 are made in one piece with the link shaft 16 (Fig. 5). The inner guide faces 17 of the said links are cylindrically formed and serve as guides for the correspondingly formed sliding blocks 12 inserted from the side. The sliding blocks are thus secured against giving way in lateral direction, the jamming of said sliding blocks which may be produced through the concur-

rence of the forces upon the eccentric rod being thus avoided as the sliding block may adjust itself to the corresponding angle in the cylindrical guide.

- 5 The link shaft 16 can be oscillated in the bearings 18 mounted upon the middle support of the bed plate 5. With this object in view a lever 19 is fixed at the middle of the link-shaft and carries at its end a nut 21
 10 adapted to oscillate in a fork around the pin 20. This nut can be displaced by the hand-wheel 22 by means of a spindle 23, the lever 19 being thus brought to the proper position for the desired direction of rotation of the
 15 engine. The spindle 23 is mounted in a bearing 25 adapted to pivot around the pin 26 in a fork-shaped part of the column 24 fixed upon the bed plate 5.

When the crank shaft 6 revolves the connecting rods 15 are operated by the eccentrics, said connecting rods actuating the guide rods 28 mounted in the transverse guide bars 27 fixed between the two middle columns 4 of the engine; each of said guide rods 28 transmitting, through the intermediary of a connecting rod 29 and of a lever 30, an oscillating motion to the lay shafts 31 of either side of the engine. The cams 32, 32' and 32'' required for the operation of the 30 valves of each compound engine, indicated in dotted lines in Figs. 1 and 2, are mounted upon said lay shafts.

Fig. 6 shows a diagram of the valve gear in the position for the forward motion of the engine. For clearness sake the diagram is shown for infinite length of connecting rods as shown in the figures and only for the top side of the cylinders. The operation of the valve gear is then as follows:

- 40 In the drawn-out position of the crank the high-pressure crank stands according to the position *a* of the centre of the eccentric, which is always displaced 180° oppositely to the position of the crank, in a position just
 45 before the upper dead centre is reached, the pin 14 being in the position *a'*. The cam 32 of the inlet valve of the high-pressure cylinder is about to lift the roller and to open thus the inlet valve. Upon further rotation the high pressure crank reaches the upper dead centre position so that the centre of
 50 the eccentric attains the position *b* and the pin 14 the position *b'*; the inlet valve is now open. In the succeeding position *c'* of pin
 55 14, the inlet valve is completely opened and now the direction of the lay shaft 31 is being reversed. When the rotation of the crank shaft continues, the inlet valve begins to close and is closed in position *d'* according
 60 to the position *d* of the centre of the eccentric, the steam admission to the high-pressure cylinder being terminated. This is cut off. Now the expansion in the high pressure cylinder begins which continues until
 65 the pin 14 arrives at the position *c'* and the

intermediary valve 34 begins to open so that the steam may pass from the high-pressure to the low-pressure cylinder the crank of the latter has arrived in the meantime in close proximity to the upper dead centre. At the succeeding point *f* the low-pressure piston is at the upper dead centre and the high-pressure piston is at the lower dead centre. Points *g'*, *g''* designate the lower reversing position of the connecting rod 15. In this position the intermediary valve is completely opened by the cam 32'. This is exhaust for the high-pressure cylinder and admission for the low-pressure cylinder and this valve closes again when pin 14 reaches position *h'*. In the high-pressure cylinder the compression begins and continues and in the low-pressure cylinder the admission is terminated at the same time and the expansion begins. In the position *i*, cam 32'' opens the low-pressure outlet valve so that the steam may escape to the condenser or into the atmosphere. When the rotation continues, the next admission to the high-pressure cylinder takes place from point *a* to *d*, but the steam escape from the low-pressure cylinder is terminated only at point *k* by the closing of the outlet valve, and the compression begins which continues until at point *e* the admission of the steam from the high-pressure cylinder begins again as above described.

For back-motion the operation is the same with the exception that pin 14 describes a curve which is displaced 90° with regard to the curve for forward motion and inclined to the right. The several points corresponding to the backward motion are here designated by *bwd*.

In comparison with the marine steam engines of usual construction which comprises a separate link for each steam cylinder, each link being mounted upon a separate shaft or upon a separate pin, the marine steam engine of the improved construction described presents the advantage that the distributing arrangement can be constructed in a very simple and compact manner. Owing to the simplification of the valve gear the adjusting of the link motion becomes more exact and much easier.

I claim:

1. In a marine-steam-engine comprising in combination two units each of one compound engine, a lay shaft for each unit, a reversing gear for both units situated at the middle of the two units, one eccentric at each side of the reversing gear, rods for connecting said eccentrics with the lay shaft of each unit adapted to operate said lay shaft, and cams on each lay shaft for operating the valves in each of the compound engines.

2. In a marine-steam-engine comprising in combination two units each of one com-

pound engine, a lay shaft for each unit, a reversing gear for both units situated at the middle of the two units consisting of one link for each compound engine, of a shaft 5 connecting the two links and of means for adjusting said shaft, one eccentric at each side of the reversing gear, rods for connecting said eccentrics with the lay shaft of each unit adapted to operate said shaft, and cams 10 on each lay shaft for operating the valves in each of the compound engines.

3. In a marine-steam-engine comprising in combination two units each of one compound engine, a lay shaft for each unit, a

reversing gear for both units situated at the 15 middle of the two units consisting of one link for each compound engine having cylindrical hollow guides, sliding blocks in said guides, a shaft connecting the two links and means for adjusting said shaft, one eccentric 20 at each side of the reversing gear, rods for connecting said eccentrics with the lay shaft of each unit adapted to operate said lay shaft, and cams on each lay shaft for 25 operating the valves in each of the compound engines.

In testimony whereof I affix my signature.

HUGO LENTZ.
